(57) **CLAIM**

The ornamental design for a roof bracket, as shown and described.

DESCRIPTION

FIG. 1 is a rear perspective view of our new design for a roof bracket;

FIG. 2 is a top plan view of our new invention;

FIG. 3 is a bottom plan view of our new invention;

FIG. 4 is a front elevation view of our new invention;

FIG. 5 is a rear elevation view of our new invention;

FIG. 6 is a right side elevation view of our new invention; and,

FIG. 7 is a left side elevation view of our new invention. The broken lines are included for the purpose of showing materials in the environment that form no part of the claimed design.
